TOOL FOR REFRIGERATOR TRAYS

Charles C. Thomas, Detroit, Mich., assignor to
Kelvinator Corporation, Detroit, Mich., a corporation of Michigan

Application February 21, 1934, Serial No. 712,359

3 Claims. (Cl. 254—131)

This invention relates to devices for use with mechanical refrigerators and more particularly to devices for facilitating the removal of ice trays from the ice freezing compartment.

5 In mechanical refrigerators and the like, the ice trays, due to the accumulation of frost about the ice trays and between the ice trays and supporting surface of the evaporator, frequently become fast or substantially frozen within the ice tray compartment of the evaporator, with the result that considerable difficulty is encountered in their removal.

10 One of the objects of the present invention is to provide a new and useful means for facilitating the removal of ice trays from the ice tray compartment of refrigerator evaporators without injury to the ice pans or evaporator.

Another object is to provide an ice tray lifting device which by means of a slight movement will 15 quickly and easily break the accumulation of ice and frost about the ice tray and permit easy removal of the tray from the ice tray compartment.

A further object is to provide a new and improved means for use with a refrigerator ice tray for raising the tray a sufficient amount to rupture the frost and ice which may have accumulated between the ice tray and evaporator, and thereby permit easy and unhindered removal of 20 the ice tray from the ice freezing compartment.

A still further object is to provide a means for facilitating the removal of ice trays from the ice freezing compartment of a refrigerator evaporator, which is simple in construction and 25 economical to manufacture, and which may be associated with the ice tray at the time of inserting the tray in the evaporator, or which may be used as a utility device after freezing has taken place.

30 With the above and other objects in view, the present invention consists of certain features of construction and combinations of parts which will be apparent, to those skilled in the art to which the invention appertains, from the following detailed description, in conjunction with the appended drawing, in which:

Figure 1 is a fragmentary front elevation of a refrigerator evaporator and ice trays each 35 having one form of the ice tray lifter device associated therewith;

Figure 2 is a section taken through the evaporator on line 2—2 shown in Figure 1, showing the ice tray in side elevation and in its normal 40 and raised position, a portion of the tray being

broken away to show the engagement of the lifting device therewith;

Figure 3 is a section similar to Figure 2, but showing another form of the lifting device of the present invention; and

Figure 4 is a perspective view of reduced size of the lifting device shown in Figure 3.

Referring to the accompanying drawing in which like numerals refer to like parts throughout the several views, I have shown in Figures 10 1, 2, and 3 an evaporator 10 of a mechanical refrigerator having ice freezing and tray compartments 11 in which ice trays 12 are disposed, there being in the construction shown for illustration an ice tray in each compartment. 15

The ice tray may be of any suitable construction such as that shown in the drawing in which the side and end walls are provided with outwardly projecting flanges 13. In the construction here shown the flanges 13 are formed with 20 down turned edges 14. However, such down turned edges are not essential to efficient operation of the device of the present invention.

The ice tray lifting device A shown in Figures 25 1 and 2 is preferably formed from suitable strap or bar material bent to a U-shape to provide a gripping portion 15 and sides or legs 16 which may be disposed at opposite sides of the tray body, but comparatively close to the side walls as indicated in Figure 1, to underlie the flanges 30 13. The legs 16 are bent upwardly at a substantial angle, the bend in each forming fulcrum portion 17. The extremities of the legs 16 are preferably formed to an accurate shape to provide tray engaging portions 18 which are disposed to underlie the flanges 13 of the ice tray, the side flanges 14 when formed on the ice tray, forming means for locating the tray engaging portions 18. 35

Normally, the ice tray lifting device A assumes the position indicated in solid outline in Figure 2, with the fulcrum portions 17 and tray engaging portions 18 engaging the supporting surface 19 of the evaporator 10 and the ice tray flanges 13, respectively, and with the portions of the legs 16 which are inwardly of the fulcrum portions 17 disposed at an angle to the evaporator surface 19. 40

Should it be found when it is desired to remove the ice tray, that the ice tray is stuck or frozen to the evaporator surface 19 or that the frost accumulation is so thick that the ice tray cannot be withdrawn from the freezing and ice tray compartment 11, it is only necessary to exert a slight downward pressure on the gripping portion 50 55 55

15, thus producing a fulcrum action whereby the upwardly bent portions of the legs 18 swing forwardly about the fulcrum portions 17 as an axis, and bodily raise the ice pan 12 as indicated in 5 dotted outline in Figure 2, thus rupturing the ice or frost accumulation and permitting the ice tray to be easily withdrawn from the ice tray compartment 11.

The lifting device is preferably so formed that 10 the horizontal gripping portion 15 is upwardly offset so that such portion is disposed relatively close to the forward flange 14 of the ice tray, whereby, when the hand is inverted and the flange 14 engaged with the fingers, the gripping portion 15 may be engaged by the thumb and downward pressure exerted thereon. By forming the lifting device in this manner, the tray may be raised to 15 break the ice or frost accumulation and withdrawn in practically a single operation.

20 If desired, the gripping portion 15 may be provided with a non-metallic sleeve 20.

In the modified form illustrated in Figures 3 and 4, the operation of lifting the ice tray is reversed, that is, the device is moved upwardly instead of downwardly. In this device, the legs 21 which extend along the sides of the ice tray 12 from the horizontal gripping portion 22 disposed adjacent to the front of the tray, normally seat on the supporting surface 19 of the evaporator 25. The legs 21 are bent upwardly in any suitable manner providing humps or inverted V-shaped portions a short distance from their extremities or evaporator shelf engaging portions 23, to provide tray engaging portions 24 which underlie the 30 flanges 13 of the ice tray 12. When a relatively weak lifting force is applied upon the gripping portion 22, the apex 24 of each hump or inverted V portion engages the adjacent flange 13 of the tray and thus raises the tray, as indicated in dotted outline in Figure 3, to rupture the accumulation of ice or frost.

The gripping portion 22 of the device B, like 35 in the device A, may if desired, be provided with a non-metallic sleeve 25. In this modification of the device, the palm of the hand may be engaged with the lower side of the gripping portion 22 while the fingers are engaged with the forward flange 14, as in withdrawing the ice tray, so that 40 upon a slight upward movement of the palm, the lifting device will be tilted upwardly about the evaporator engaging portions 23 of the device.

The lifting devices described are so constructed that they may be disposed about the ice tray at the time the tray is inserted in the freezing compartment, or they may be utilized as a utility device and inserted after the fluid in the tray has 45 become frozen.

It is to be noted that in each of the lifting devices described, I have provided at each side, a fulcrum or evaporator engaging portion and a

tray flange engaging portion suitably offset longitudinally of the legs, and a lever portion, which upon swinging movement about the fulcrum portions, causes the tray engaging portions to exert upward pressure against the tray flanges to thereby break the accumulation of frost or ice and facilitate and permit easy withdrawal of the ice tray from the evaporator.

The lifting device is simple in construction and may be economically produced from a single piece 10 or separate pieces of metal.

Also, each of the devices described are so shaped that the lifting and withdrawal of the ice tray may be performed in practically a single operation.

15 While I have shown and described only two of the forms which the present invention may assume, it is to be understood that the invention may be embodied without departing from the spirit and scope of the invention, as defined by 20 the appended claims.

What I claim is:

1. A device for separating an ice tray from the shelf of a freezing compartment comprising a substantially U-shaped member providing a pair 25 of parallel legs spaced apart to extend adjacent opposite sides of an ice tray, a gripping portion extending between said legs adjacent one end of the tray and said legs comprising tray engaging portions and adjacent shelf engaging portions so 30 disposed that a leverage is obtained for separating the ice tray from the shelf by a relatively weak force applied to said gripping portion.

2. A device for separating an ice tray from the shelf of a freezing compartment comprising a 35 substantially U-shaped member providing a pair of parallel legs spaced apart to extend adjacent opposite sides of an ice tray, a gripping portion extending between said legs adjacent one end of the tray, and upturned end portions on each of 40 said legs for engaging a portion of the tray whereby the junction of each leg and its upturned end portion forms a fulcrum point engageable on the shelf to provide leverage and the tray may be separated from the shelf by a relatively weak force 45 applied downwardly on the gripping portion.

3. A device for separating an ice tray from the shelf of a freezing compartment comprising a substantially U-shaped member providing a pair of parallel legs spaced apart to extend adjacent opposite sides of an ice tray, a gripping portion extending between said legs adjacent one end of the tray and humps or inverted V portions provided in the legs a short distance from the extremities thereof for engaging the laterally projecting 55 flanges of the tray to separate it from the shelf when a relatively weak lifting force is exerted upon the gripping portion to rotate the legs about their shelf engaging extremities as fulcrum points.

CHARLES C. THOMAS.
